BAR SUPPORT

Robert R. Robertson, Chicago Heights, Ill.

Application July 11, 1930, Serial No. 467,148
Renewed April 2, 1934

1 Claim. (Cl. 94—8)

This invention relates to an improved reinforcing bar support and more particularly to supports for holding marginal supporting bars in position at different elevations in the longitudinal margins of a concrete road and at a predetermined distance above the top surface of the road sub-grade.

It is an object of this invention to provide an improved marginal bar support comprising a stake having a spacing arm for contact with a road form whereby a bar supporting member on the stake is provided with bar retaining fingers adapted to be moved into locking position to retain bars in place in spaced relation at given distances above the road sub-grade and at predetermined distances from the side of the road.

It is also an object of this invention to provide an improved marginal reinforcing bar support of flat bar metal having rigidly engaged or formed thereon a flange member having spaced bar receiving openings therein and a stop flange formed thereon for coaction with the top surface of the road sub-grade for the purpose of properly positioning the support so that the reinforcing bars carried thereby may be positioned at predetermined elevations and at set distances from the margin of a body section of a concrete road.

It is a further object of this invention to provide a marginal reinforcing bar support constructed of flat metal to prevent rotation of the support when engaged in a concrete road, said support including an apertured bar supporting sheet metal flange having one margin thereof bent and folded in clamping relation around a portion of the flat metal stake portion of the support, with said apertured flange having flexible fingers struck therefrom and normally positioned to permit marginal reinforcing bars to be engaged in the openings and adapted to be bent into clamping position after the bars are in place to retain the same against removal from the support.

It is an important object of this invention to provide an improved type of marginal reinforcing bar support constructed of metal embracing a stake and an integral spacing arm with said stake having integrally formed or rigidly secured thereto an apertured bar supporting flange provided with bar locking members and with a stop flange for limiting the insertion of the stake portion of the support into a road sub-grade for the purpose of properly spacing the marginal reinforcing bars vertically within

the marginal section of the concrete body portion of the road.

Other and further important objects of this invention will be apparent from the disclosures in the specification and the accompanying drawing.

The invention (in a preferred form) is illustrated in the drawing and hereinafter more fully described.

On the drawing:

Figure 1 is a fragmentary vertical cross section of a concrete road having embedded therein improved marginal reinforcing bar supports embodying the principles of this invention.

Figure 2 is a fragmentary top plan view taken on line II—II of Figure 1.

Figure 3 is a side elevation of an improved marginal reinforcing bar support embodying the principles of this invention.

Figure 4 is a front elevation of the support illustrating the retaining fingers in open position.

Figure 5 is a detailed sectional view of the support taken on line V—V of Figure 3.

Figure 6 is a fragmentary side elevation of a modified form of support.

As shown on the drawing:

The reference numeral 1 indicates a concrete road sub-grade having mounted thereon longitudinally disposed and laterally spaced forms 2 between which concrete is to be poured upon the sub-grade to form the body section 3 of the concrete road. For the purpose of reinforcing the longitudinal margin of the body section 3 of the concrete road it is desirable to embed marginal reinforcing rods or bars 4 at spaced elevations above the top surface of the road sub-grade 1 and at a predetermined distance from the inner surfaces of the forms 2. For supporting the reinforcing rods in place at spaced intervals within the longitudinal margin of the concrete section 3 of the road a plurality of improved marginal reinforcing bar supports are engaged in the road sub-grade, in contacting or coacting relation with the inner faces of the forms 2 as clearly illustrated in Figures 1 and 2 of the drawing.

The improved marginal reinforcing bar support comprises a stake or pin 5 constructed of flat metal and having the lower end thereof chamfered or beveled or otherwise pointed at 6 to form a point or tip to permit the stake to be readily driven into the sub-grade 1. The stake or pin 5 is constructed of flat metal so that when the same is embedded in the concrete or driven into the road sub-grade 1 it will not ro-

tate or turn. The upper end of the flat metal stake or pin 5 is bent at right angles to provide a spacing arm 7 the end of which is adapted to contact the inner surface of a concrete form 2 when the pointed end of the stake 5 is driven into the road sub-grade as illustrated in Figure 1.

Rigidly engaged on the upper portion of the flat metal stake 5 below the arm 7 is a bar supporting member constructed of sheet metal one longitudinal margin of which is bent and formed around the flat body section of the stake 5 and is rigidly clamped thereon against movement to form a supporting sleeve or tube 8 having a longitudinal slot 9 formed therein.

Rigidly formed at right angles along one longitudinal margin of the slot 9 and projecting in a direction opposite from the direction of projection of the spacing arm 7 is a bar supporting flange or plate 10 the lower end of which is bent outwardly at right angles to provide a stop flange or foot 11. The stop flange or foot 11 is also positioned at substantially right angles to the front face of the flat stake 5 as illustrated in Figure 3 and acts as a stop for limiting the driving of the pointed end of the stake 5 into the road sub-grade 1. The flange plate 10 is provided with a plurality of bar supporting apertures or notches 12 which open through the outer longitudinal edge of the flange 10. The flange 10 is stamped or cut so as to leave a retaining finger or lug 13 at the outer end of each of the notches or openings 12. The retaining finger 13 is normally bent out of the plane of the flange 10 as illustrated in Figure 4 to leave an opening or mouth for each of the openings 12 to permit a marginal reinforcing rod or bar 4 to be inserted into the opening similar to the arrangement illustrated in Figure 1. After a marginal reinforcing bar 4 is engaged in one of the openings of the supporting plate or flange 10 the retaining lug or locking finger 13 is bent inwardly from the position illustrated in Figure 4 to be disposed substantially in the plane of the supporting flange 10 to substantially close the open end of the notch 12 thereby locking or retaining the reinforcing bar 4 in position.

As illustrated in Figure 3 the bar supporting flange 10 is provided with two sets of openings or notches 12 for the purpose of supporting a pair of marginal reinforcing bars or rods 4 in spaced parallel relation one above the other when said rods are supported by means of a plurality of spaced supports similar to the arrangement illustrated in Figure 2.

In practice the improved supports are driven into the sub-grade 1 in a line parallel to the marginal forms 2 with the outer ends of the spacing arms 7 in contact with the inner faces of the forms 2. Stakes 5 are driven into the sub-grade 1 until the stop flange or foot 11 of each of the stakes comes into contact with the top surface of the sub-grade to limit the further driving of the stake downwardly. The improved supports thus mounted in position upon the sub-grade with the arms of the support contacting the inner surface of the form 2 are arranged to receive marginal reinforcing rods 4 inserted in the open notches 12, with said rods extending from one support to another. The reinforcing rods 4 are thus supported in parallel relation at predetermined distances above the top surface of the sub-grade and at required distances from the side of the road. After the marginal reinforcing rods are engaged in the supports the re-

taining fingers or lugs 13 are bent downwardly from the position illustrated in Figure 4 into closed position as illustrated in Figure 1 thereby locking or retaining the marginal reinforcing bars in place.

As illustrated in Figure 1 of the drawing a row of marginal reinforcing bar supports is engaged on the sub-grade adjacent the inner side of each of the forms 2 to support marginal reinforcing bars at spaced distances above the sub-grade and to the inside of the forms 2. Concrete is then poured upon the sub-grade and between the forms 2 to form the body section 3 of the road. As the concrete is deposited in place it flows outwardly toward the form thereby causing the reinforcing rods 4 to be pushed against the supporting sleeves 8 forming part of the bar supports. The flat formation of the stakes 5 and the spacing arms 7 forming a part thereof prevent the supports from rotating or twisting after they are engaged in position. It will furthermore be noted that the square outer ends of the spacing arms 7 are adapted to bear flatly against the inner face of the side forms 2 to further act as a means for preventing the supports from rotating or twisting out of position.

Figure 6 illustrates a modified form of support, of unitary construction comprising an angle body section consisting of a stake flange 14 and a bar supporting plate or flange 15 disposed at substantially right angles thereto. The lower end of the stake flange 14 is cut away or tapered at 16 and at its lower end joins the lower end of a tapered section 17 formed on the lower end of the supporting flange 15. The two tapered portions 16 and 17 form a spike or tip to facilitate driving the support into a road sub-grade. Integrally formed at right angles to the upper end of the stake flange 14 is a spacing arm 18 which is adapted, when the support is in position, to have the end thereof in contact with the inner surface of the concrete form 2 similar to the arrangement illustrated in Figure 1. The spacing arm serves to hold the body portion of the support properly spaced from the side of the road for the supporting of marginal reinforcing members.

The supporting flange 15 is provided with a plurality of bar supporting openings or notches 19 which open through the outer longitudinal edge of the flange 15. The flange 15 is stamped or cut so as to leave a retaining finger or lug 20 at the mouth or outer end of each of the openings 19. The fingers 20 are normally bent out of the plane of the flange 15 to permit the insertion of marginal reinforcing bar or rods in the openings 19. After the placing of the reinforcing members in the openings 19, the fingers 20 are bent into the plane of the flange 15 to thereby close the mouths of said openings 19 to lock or retain the reinforcing members in position.

Struck from the supporting flange 15 at a point between the lower openings 19 and the tapered end 17, is a stop flange or foot 21, which serves as a stop for limiting the driving of the tapered end of the support into the road sub-grade, to properly position the reinforcing members at required elevations above the sub-grade to be embedded in concrete.

It will of course be understood that various details of construction may be varied through a wide range without departing from the principles of this invention and it is therefore not the purpose to limit the patent granted hereon

otherwise than necessitated by the scope of the appended claim.

I claim as my invention:

5 A reinforcing bar support adapted to cooperate with a marginal road form, said support consisting of a flat metal stake having its width decreased at one end to provide a driven point and having a portion bent normal to the longitudinal axis of said stake to provide an arm adapted to 80 rest against a road form, the other end of said stake being substantially straight to provide

means cooperating with the road form and the driven end of the stake to prevent turning of the driven stake, and a sheet metal member having a part thereof bent clamped to said stake providing a wing directed oppositely to said normally bent portion of said stake, said wing having a plurality of vertically spaced notches and having integrally connected bendable fingers providing closure means for the notches.
